(57) **CLAIM**

The ornamental design for a vehicle airbag system, as shown and described.

DESCRIPTION

FIG. 1 is a top perspective view of a vehicle airbag system; FIG. 2 is a bottom perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is top perspective view shown with environment of a vehicle seat; and,

FIG. 10 is a left-side elevation view shown with environment of a vehicle seat.

The dashed broken lines depict portions of the vehicle airbag system and environment that form no part of the claimed design.

1 Claim, 10 Drawing Sheets
